UNITED STATES PATENT OFFICE.

WILLIAM F. SHOLL, OF HUBBELL, NEBRASKA.

PHONOGRAPH-TABLET SUPPORT AND REMOVER.

1,282,473.

Specification of Letters Patent. Patented Oct. 22, 1918.

Application filed May 20, 1918. Serial No. 235,692.

To all whom it may concern:

Be it known that I, WILLIAM F. SHOLL, a citizen of the United States, residing at Hubbell, in the county of Thayer and State of Nebraska, have invented certain new and useful Improvements in Phonograph-Tablet Supports and Removers, of which the following is a specification.

This invention relates to a device for supporting and elevating disk records or tablets, the device coöperating with the usual turn-table.

The object of the invention is to facilitate removal of the tablet from the phonograph, said term being employed broadly to designate talking machines of the disk type.

The invention also consists in the novel features of construction hereinafter described, pointed out in the claims and shown in the accompanying drawings, in which:

Figure 1 is a plan view of a turn table with my device applied thereto.

Fig. 2 is a side elevation of the parts shown in plan in Fig. 1.

Fig. 3 is a plan view of the mechanism arranged beneath the turn-table, the latter being removed, and parts being in section, the parts occupying the position assumed when the record is elevated.

Fig. 4 is a vertical section showing the tablet in raised position on the line 4—4 of Fig. 3.

Figs. 5 and 6 are detail perspective views of lifting rings.

In the drawings 1 designates the top of the phonograph casing, having a turn-table 2, with depending flange 3. Said table revolves with the usual pivot post 4. Surrounding this post and beneath the table 2 is an annular wall 5, provided with vertical slots 6 and oblique slots 7.

Placed within said wall and concentric with the post 4, and out of frictional contact with both post and wall, is a flat ring 8 having projecting pins 9 adapted to work in the slots 7. Resting loosely on the ring 8 is a second ring 10 having laterally projecting pins 11 that work in the vertical slots 6.

Countersunk slots or openings 12 are formed in the turn-table, which comprises the usual felt covering and through these openings work headed pins 13, the heads normally resting below the surface of the table so that the tablet A will rest on the felt covering. To the lower ends of these

pins is connected a ring 14, normally out of contact with the ring 10.

An angled vertical bracket 15 is mounted on the casing 1 and carries a sleeve 16 in which rotates a shaft 17 having a crank portion 18, and bent at its free end to form a thumb piece 19. The crank portion 18 is connected by a rod 20 to a pin 9^a carried by the ring 8 and formed by extending and applying an eylet to one of the pins 9.

A brake shoe 21 coöperates with the inner face of the flange 3 of the turn-table, as in Fig. 3, and is connected by pivoted links 22 and 23 with the shaft 17.

The operation of the device is as follows:

Normally the tablet rests in the usual position, with the brake off. When the record is to be removed the piece 19 is gripped between the thumb and forefinger, the shaft 17 drawn along the sleeve 16 from the position shown in Fig. 1 to that in Fig. 3 and then given a quarter turn to lock the crank portion 18 against the angle of the bracket 15 as in Fig. 3. Through the links 22 and 23 the brake is applied and at the same time disk 8 is rotated and lifted by the pins 9, 9^a working in the slots 7. This movement lifts vertically the ring 10, which is prevented from rotation by the pins 11 traveling in the vertical slots. The ring 10 will engage the pins 13 as the brake is applied and lifts the pins 13 which in turn elevate the record to a point where it will not quite clear pivot post 4. The edge of the record can then be readily grasped and removed and a new record placed in position.

Lowering of the new record by reverse operation, aided by spring 24, releases the brake and restarts the machine.

While the automatic operation of the brake in connection with the lifting and lowering device is a great convenience it is not essential to this portion of the device that the brake be employed as shown, and I desire the option of omitting the brake actuating feature in cheaper forms of the device. It is also obvious that the tablet may be engaged directly as shown by the heads of the pins 13 or by any tablet supporting means that may be placed on said pins.

What I claim is:

1. In a device of the kind described, a tablet receiving turn-table, pins working through said table, a plate or ring having a

compound rotatable and vertical movement adapted to lift said pins, and means mounted adjacent said table for imparting said movement to said ring.

- 5 2. A device of the kind described, comprising a pivot post and a turntable having a depending flange, a wall surrounding said post and below the turn-table and having vertical and oblique slots, rings arranged 15 therein and having pins engaging respectively the said slots and engaging each other, means for rotating the ring the pins of

which coöperate with the oblique slots, a third ring, pins carried by the third mentioned ring, working through the turn-table and adapted to be engaged by the ring having the pins working in the vertical slot, a brake adapted to engage the flange of the turntable and means connecting the brake with the ring operating means, as and for 20 the purpose set forth.

In testimony whereof I affix my signature:

WILLIAM F. SHOLL.
